UNITED STATES PATENT OFFICE.

CONRAD KOHLER, OF ZURICH, SWITZERLAND.

STEAM BOILER WITH FORCED-DRAFT FURNACE.

1,423,335.

Specification of Letters Patent.

Patented July 18, 1922.

Application filed March 17, 1920. Serial No. 366,659.

To all whom it may concern:

Be it known that I, CONRAD KOHLER, a citizen of the Republic of Switzerland, residing at Hardturmstrasse 19, Zurich, Switzerland, have invented certain new and useful Improvements in Steam Boilers with Forced-Draft Furnaces; and I do hereby declare the following to be a clear, full, and exact description of the invention, such as will enable others skilled in the art to which it appertains to make and use the same, reference being had to the accompanying drawing and to letters or figures of reference marked thereon, which form a part of this specification.

This invention relates to improvements in steam boilers with forced draft furnaces and particularly to draft-furnaces in which the air is admitted into the ash-pit under the grate for increasing the draft and promoting combustion.

Steam boilers with forced draft-furnaces of the type mentioned above present the disadvantage that the opening of the fire door is always dangerous, as flames or at least noxious gases may be driven out by the forced draft when the fire door is opened.

The object of the present invention is to eliminate the drawback referred to. To this end a blast device is provided which is connected to the fire box previous to the opening of the fire door, whilst the air current from the blower to the ash-pit is cut off. The blast device may be worked by the compressed air from the under-grate blower, in which case a change-over device is provided that is adapted to effect a connection between blower and blast-device and to close the connection between blower and ash-pit. The blast-device may also be worked by means of the draft induced by the running speed of the vehicle on which the boiler is mounted.

The accompanying drawing illustrates by way of example several modes of carrying out the invention. All these are applied to steam-locomotives, in which the danger, that the flame or noxious gases on opening the furnace door are driven into the cab, exists in a higher degree because the air-current induced by the speed of the locomotive produces a depression in the cab.

In the drawing:

Fig. 1 is a diagrammatic longitudinal section through a locomotive fitted with improvements according to the invention.

Fig. 2 is a modification of a detail of Fig. 4.

Fig. 3 is a longitudinal section through a locomotive showing a modified arrangement. 60

Fig. 4 is a longitudinal section through the lower part of the fire-box illustrating special means for reducing the pressure in the box.

Fig. 5 is a view similar to Fig. 4, showing 65 under-pressure means for the ash pit.

An eight wheel locomotive is shown dia-

grammatically in Fig. 1. It is driven by a steam-turbine 1 placed on the front of the locomotive, the details of the drive are not 70

shown. When working normally the ex-
haust steam from the steam turbine is led
to a surface-condenser (not shown in the
drawing). When the locomotive is stopping
or when an increase of the draft in the boiler 75

furnace is necessary, the exhaust steam is
led to a blast-device 2, from where it passes
through the stack and, acting as an ejector,
causes the gases in the smoke box 4 to escape
through the stack. When working normally 80

a blower 5 compresses air and forces it
through pipe 6 into the ash-pit 7. From
there it passes through the gate 8 and the
fuel. The gases of combustion flow from the
fire-box 9 through the boiler tubes 10 into 85

the smoke box 4 and escape through the
chimney 3. In order to prevent the noxious
gases from passing through the door 11 of
the fire box into the cab when the door 11 90

is opened, it is necessary to stop first of all
the blower 5 or to stop at least its effect on
the combustion by closing the conduit 6 by 95

means of a flap valve 12. Then the flap
valve 14 inserted in the conduit 13 which
has been closed up till then, is opened to

eliminate quickly any over-pressure in the
fire-box 9 and to generate an under-pressure
in this box. Fig. 1 shows the connections
between the parts arranged and set in the
above described manner. The compressed 100

air from the blower 5 flows along conduit 13
into the blast device 2 arranged inside the
smoke box 4, the combustion gases contained
in the fire box 9, the boiler tubes 10, and the
smoke box 4, are carried away with the air 105

into the stack 3 and the desired under-pres-
sure is thus generated inside the fire-box 9.

The door 11 may now be opened without
fear that flames or noxious gases will burst
into the cab. To ensure that flap valve 12 110

has been closed and flap valve 14 opened be-
fore the door 11 is opened, a lever 15 may be

arranged in front of the door 11 by means of which lever and connecting rods 16, 17 connecting said lever up to the valves 12 and 14, the latter are actuated. In order to open 5 the door 11, lever 15 has first to be rocked on its fulcrum 18 towards the left which movement brings the valves 12 and 14 into the desired positions. The furnace door 11 is locked until after this movement has been 10 carried out.

When the furnace door 11 is to be opened during the running of the locomotive at full speed, under-pressure is produced by a pipe 21 the axis of the opening of which is ar- 15 ranged vertically as shown in Fig. 4, or which is bent towards the rear as shown in Fig. 2. The current of air induced in the pipe 21 by the speed of the vehicle generates an under-pressure inside said pipe, 20 whereby combustion gases are drawn from the fire-box 9, until an under-pressure is generated therein. The conduit 21 can be closed by means of a flap-valve 23. Instead of connecting a conduit 21 to the fire-box 9, 25 a pipe 25 fitted with a flap valve 24 may be connected to the ash-pit 7, Fig. 5.

The modification of the invention shown in Fig. 3 consists in a conduit 29, that can be closed by means of a flap-valve 28, which 30 connects the ash-pit 27 with the smoke box. This construction is based on the assumption that the lifting power, to which the heated 35 gases are subjected by the draft action of the stack 30, suffices to cause a quantity of gas to be drawn out of the ash-pit by conduit 29 and to escape through the stack 30, whereby an under-pressure is generated in the ash-pit 27 and the fire-box 31, sufficient 40 to allow the fire-box door 32 to be opened without any danger. Obviously the connection 45 from the blower 33 to the ash-pit 27 has to be closed by flap-valve 34 a short time before the furnace door is opened.

I claim:

45 1. In a steam-boiler with forced draft-furnace, the combination of a furnace consisting of a fire-box with fire door and closed ash-pit, an under-grate blower, a conduit connecting the blower and ash pit, a blast device, means including said conduit connecting the ash pit with the blast device, and 50 means for opening and closing the conduit and said connecting means so that the pressure above atmospheric inside the fire box

is removed and an under-pressure is gen- 55 erated.

2. In a steam-boiler with forced draft-furnace, the combination of a furnace consisting of a fire-box with fire-door and closed 60 ash-pit, an under-grate blower, a conduit connecting blower to ash-pit, a blast device, a closing device inserted in said conduit, and means to set said closing device so that the pressure above atmospheric inside the fire-box is removed and an under-pressure is 65 generated by said blower to permit opening the fire-door without danger.

3. In a steam-boiler with forced draft-furnace, the combination of a furnace consisting of a fire-box with fire-door and closed 70 ash-pit, an under-grate blower, a conduit connecting blower to ash-pit, a blast device, a conduit connecting blower to blast device, a closing device inserted in each of said conduits, and means to set said closing devices 75 so that the pressure above atmospheric inside the fire-box is removed and an under-pressure is generated which permits opening the fire-door without danger.

4. In a steam-boiler with forced draft-furnace, the combination of a furnace consisting of a fire-box with fire-door and closed 80 ash-pit, an under-grate blower, a conduit connecting blower to ash-pit, a blast device, a conduit connecting blower to blast device, 85 a closing device inserted in each of said conduits, and means to set said closing devices so that the connections with the blower are changed over from the ash-pit to the blast device whereby an under-pressure is 90 generated into the fire-box which permits opening the fire-door without danger.

5. In a steam-boiler with forced draft-furnace, the combination of a furnace consisting of a fire-box with fire-door and closed 95 ash-pit, an under-grate blower, a conduit connecting blower to ash-pit, a blast device, a conduit connecting blower to blast device, a closing device inserted in each of said conduits, and means to prevent the fire-door 100 from being opened until after said closing devices have been set by said means so that the pressure above atmospheric inside the fire-box is removed and an under-pressure is generated.

In testimony that I claim the foregoing as my invention, I have signed my name.

CONRAD KOHLER.
